UNITED STATES PATENT OFFICE.

THOMAS CRANEY, OF BAY CITY, MICHIGAN.

BOILER-CLEANER AND CIRCULATING APPARATUS.

SPECIFICATION forming part of Letters Patent No. 254,118, dated February 28, 1882.

Application filed July 8, 1881. (No model.)

To all whom it may concern:

Be it known that I, THOMAS CRANEY, of Bay City, in the county of Bay and State of Michigan, have invented an Improvement in 5 Boiler-Cleaners and Circulating Apparatus, of which the following is a specification.

The nature of this invention relates to certain new and useful improvements in the construction of devices designed to be attached to 10 steam-generators for the purpose of removing impurities which are separated from the water during the process of steam-making, and thus to prevent the incrustation of the boilers.

The invention consists in the peculiar construction, arrangement, and various combinations of the parts, all as more fully hereinafter set forth.

Figure 1 is a perspective of a boiler provided with my improvement. Fig. 2 is a vertical longitudinal central section through the injector-drum.

In the accompanying drawings, which form a part of this specification, A represents a steam generator or boiler. Near the water-line and 25 within the boiler-shell I secure a coil of pipe, C, one end of which projects through the boiler, and is connected with and forms a part of the feed-water pipe B, while its opposite end extends through the shell and leads into the drum 30 D, and has secured to it within such drum one member of the injector F, while the opposite member of the injector F is secured to a pipe, G, which enters the opposite side or end of the drum, passing thence down and into the boiler-shell 35 below the water-line, and in boilers which are provided with a mud-pipe it is connected thereto.

H is a surface-pan located within the boiler at about the water-line, or just below it, and is 40 secured to the end of a pipe, I, which extends thence through the boiler into the drum D, as shown in dotted lines.

The pipe G and feed-pipe B may be provided with valves a b c, as shown, and drum D may 45 be provided with an exhaust-pipe or blow-off pipe and valve J, if desired.

In practice we will suppose the valves a c to be opened and the valve b closed, a proper connection being made at d with a pump or injector for supplying water to the boiler. During 50 the process of generating the steam, and

while supplying the boiler with water, it passes through the feed-water pipe B into the coil C within the boiler, and thence to the injector-drum D, through which it is forced by the action of the pump through the injector at a great velocity, passing out through the pipe G, and thence into the boiler below the water-line. During this action the rapid passage of the feed-water through the injector F in the drum 55 D creates a suction and circulation through the pipe I, as in a siphon, drawing directly from the surface-pan and creating a circulation of water through such pipe I into the drum D, from which a portion of the water contained 60 therein is continually being passed off through the pipe G into the boiler, while sediment and other foreign matter will settle to a great extent in the bottom of the drum, from which it 65 may be blown off, as may be desired, through the pipe J; and in this construction there is a continuous circulation of water from the surface of the water in the boiler through the various pipes and the injector-drum back into 70 the boiler, continually separating the impurities from the water, which are held in suspension therein and are gradually deposited within the drum. Should it be found that this drum 75 was insufficient to receive the amount of deposit of foreign matter—as where oily or muddy water is necessarily used—another drum may be interposed between this drum and the boiler; and it will be found that a generator provided with this attachment will very rarely 80 become incrusted, as the circulation is so positive and complete that the impurities are deposited within the drums provided for the purpose.

If desired, the coil C within the boiler-shell may be entirely omitted and the feed-water 85 pipe be connected directly to the injector without departing from the spirit of my invention, as the one function performed by the coil is that the water may be somewhat heated before it is delivered to the boiler. Hence it has no 90 necessary connection with the injector-drum, but assists in its effective working. While my injector-drum is placed near the top of the boiler, its location is not arbitrary, as it may be placed anywhere upon the feed-water pipe 95 between the source of supply and the point where it passes to the boiler; or the injector

may be placed in the water-supply outside of the drum, having the connection from the surface-pan and its pipe made directly with the shell of such injector, from whence the surface circulation will pass into a settling-drum.

What I claim as my invention is—

- 5 1. In a steam-generator, the combination of the supply-pipe J, drum D, injector F, pipe I, surface-pan H, and the pipe G, as and for the purpose specified.
- 10 2. In combination with the steam-generator

and its water-supply pipe, the drum D, which incloses an injector, F, said drum being connected to the boiler by the pipe G and to the surface-pan within the boiler by a pipe, I, substantially as and for the purposes set forth. 15

THOS. CRANEY.
